(57) **CLAIM**

The ornamental design for a boat anchor roller, as shown and described.

DESCRIPTION

This application is related to application Ser. No. 17/736, 710, concurrently filed herewith, and claims priority to the filing date thereof.

FIG. 1 is a front perspective view of the new design for a boat anchor roller;

FIG. 2 is a rear perspective view of the new design;

FIG. 3 is a front view of the new design;

FIG. 4 is a rear view of the new design;

FIG. 5 is a left side view of the new design;

FIG. 6 is a right side view of the new design;

FIG. 7 is a top view of the new design;

FIG. 8 is a bottom view of the new design;

FIG. 9 is a front perspective view of the new design with an anchor as environment shown in dashed lines;

FIG. 10 is a rear perspective view of the new design with an anchor as environment shown in dashed lines; and,

FIG. 11 is a front perspective view of the new design attached on a boat, with the anchor deployed and the anchor line shown as environment in dashed lines.

The broken lines shown in FIGS. 9-11 illustrate environment, and form no part of the claimed design.

1 Claim, 9 Drawing Sheets
